UNITED STATES PATENT OFFICE.

CHARLES M. MALLORY, OF TOLEDO, OHIO.

SUSPENSION-CLEVIS FOR ELEVATORS.

SPECIFICATION forming part of Letters Patent No. 250,090, dated November 29, 1881.

Application filed October 1, 1881. (No model.)

To all whom it may concern:

Be it known that I, CHARLES MARTIN MALLORY, a citizen of the United States, residing at Toledo, in the county of Lucas and State of 5 Ohio, have invented a new and Improved Suspension-Clevis for Hay-Elevators, of which the following is a specification.

The object of my invention is to provide a suspension-clevis of improved construction attached to guide-pulley, thereby rendering it less complicated and more easily hung up in a barn.

The invention will first be described in connection with the drawings, and then pointed out in the claims.

15 In the accompanying drawings, Figure 1 represents an elevation of my improved clevis put up in working position in barn, the latter being shown in vertical section. Fig. 2 is a side view, and Fig. 3 a top view of the combined 20 suspension-clevis and guide-pulley.

Similar letters refer to similar parts throughout the different views.

The guide-pulley D, with suspension-clevis c attached, is tied to a pair of rafters at peak 25 of barn, over barn-floor, serving as fulcrum or support for carrier a while hoisting hay from

wagon. The carrier a is held in position on clevis c by a little catch pulled down over it by pulley J. When the pulley J comes in contact with carrier a the latter is detached from clevis 30 c and swings back into the mow with fork full of hay. When the fork is tripped, releasing it from hay and the horse backed up, the weight P descends, causing the carrier a to promptly return to clevis c, guided by pulley D, whence 35 it is ready for another load.

Suspension-clevis c is made preferably of malleable or bar iron, and attached to guide-pulley D by rivet d.

The weights I are attached to the extending 40 ends o of the clevis c by rivet K, serving as counter-balance.

Having thus fully described my invention, I claim as new and desire to secure by Letters Patent—

45 The clevis c, provided with eyes e, extending ends o, and weights I, and combined with guide-pulley D, substantially as specified.

CHARLES MARTIN MALLORY.
